Primary Examiner — Robert M Spear(74) *Attorney, Agent, or Firm* — Henry M. Feiereisen LLC;
Ursula B. Day(57) **CLAIM**

The ornamental design for a hygiene cap, as shown and described.

DESCRIPTION

FIG. 1 is a front elevational view showing my new design;
FIG. 2 is a left side elevational view thereof, the right side being a mirror image thereof;
FIG. 3 is a rear elevational view thereof;
FIG. 4 is a front elevational view of the same design as FIG. 1, but showing the soft top bulged outward;
FIG. 5 is a top plan view thereof;
FIG. 6 is a bottom plan view thereof; and
FIG. 7 is a perspective view of thereof;
FIG. 8 is a front elevational view of my new design shown as part of a stack;
FIG. 9 is a side elevational view of the stack of FIG. 8;
FIG. 10 is a rear elevational view of the stack of FIG. 8;
FIG. 11 is a front elevational view of the stack of FIG. 8 showing the soft top bulged outward;
FIG. 12 is a top plan view of the stack of FIG. 8;
FIG. 13 is a bottom plan view of the stack of FIG. 8; and,
FIG. 14 is a top front perspective view of the stack of FIG. 8. In the drawings, the broken lines are for the purposes of illustrating environment only and form no part of the claimed design.
